UNITED STATES PATENT OFFICE.

SQUIRE BENTLEY, OF PATERSON, NEW JERSEY, ASSIGNOR OF ONE-THIRD
TO ALFRED WOODIER, OF SAME PLACE.

JACQUARD ATTACHMENT FOR LOOMS.

SPECIFICATION forming part of Letters Patent No. 519,374, dated May 8, 1894.

Application filed July 10, 1893. Serial No. 480,094. (No model.)

To all whom it may concern:

Be it known that I, SQUIRE BENTLEY, a citizen of the United States, residing in the city of Paterson, county of Passaic, and State of New Jersey, have invented a new and useful Jacquard Attachment for Looms, it comprising a device for releasing the cards from and to prevent their overlapping on the cylinders of the Jacquard machines used in weaving textile fabrics, of which the following is a specification.

My invention relates to the means employed for preventing the cards perforated with holes, laced together in continuous succession and forming the design to be woven, from overlapping or engaging with each other, as they are delivered from the cylinder of a Jacquard machine, through the card being retained upon the cylinder by the friction of the driving pins, or their becoming fouled in the holes. When overlapping of the cards occurs through failure of delivery at the proper point, the one following on the cylinder will be apt to lay above or below the detained cards, and being carried around the circuit, will arrive at the machine again in that condition, unless the fault be discovered by the operator in charge of the loom, or the weaver who would rectify the disarrangement and restore them in their proper alignment. Should the disarrangement remain undiscovered, the cards so overlapping by passing on to the cylinder, will prevent the needles of the Jacquard machine from entering their proper holes, and producing the pattern by raising the warp, or opening the shed with accuracy, producing faults in the fabrics in process of manufacture. The fact of two cards being upon the cylinder at one time and overlapping each other, may be better understood when I mention that each of the operations performed by the cards, may be different by reason of the holes cut to permit the passage of the needles through the cards to enter the holes provided in the cylinder, may be located in diverse parts of the card, so that the holes in one card may be covered by unperforated parts of the other, although possibly two or more holes may come in line 50 in which event the needles would enter those

holes but an imperfect weave would still result. As the operation of weaving is performed very rapidly the fault may not be discovered until a considerable amount of cloth may be woven. The time lost in stopping the looms and cutting out the defective parts would amount to a serious consideration, as to material wasted, and time lost.

With the application of my newly invented device to the cylinder of a Jacquard machine that loss and delay would be avoided, as it would insure the regular delivery of each card from engagement with the pins, located at each end of the cylinder, on the different faces, as the cylinder revolves. The cards necessarily being carried by the pins are apt to cling or adhere to the pins after they have performed their office or duty and after the cylinder has rotated and brought a fresh or different card in contact with the needles. At this time an outward blow, force or pressure is given by my device that effectually detaches the card from the pins or pegs and the cylinder permitting it to fall away in its proper position and alignment, with reference to the neighboring cards to which it is laced and so travel onward to repeat its duty again. This I accomplish by the device described in the following specification and illustrated in the drawings accompanying it, in which—

Figure 1, is a plan view of the cylinder, showing my device attached; with a partly broken card in engagement. Fig. 2, is a cross section of cylinder on line Z Z. Fig. 3, is an end view of a cylinder, with cards in position showing operation of device. Fig. 4, is an end view of cylinder showing cards in position, and card to be delivered fouled and caught.

Similar letters bear reference to similar parts in the drawings and specification.

I will now proceed to describe the construction of my newly invented device for insuring the proper release of the cards from the cylinder of Jacquard machine.

A. Fig. 1, represents a cylinder of Jacquard machine of the usual construction, B. B. the spindles or gudgeons upon which, it rotates, C. C. loose collars for adjusting the same in bearings formed in the Jacquard machine.

framing, D, carrying or conveying pin or pins, E, the rotating device, F, the holes to receive the needles for forming pattern, F' holes for needles forming selvage, —H— spaces between pattern and selvage holes in which space the releasing device is located.

My releasing device consists of a rod or stem N on the threaded end of which are plungers P and P', two being used at each end of the cylinder —A— and each being double ended, provided each face and end with a plunger hammer or forcing device as shown. At each end of the cylinder A near the front edge H' and in the space H between the holes F and F' are drilled transversely through the cylinder from two of the faces suitable holes L of a size sufficiently large to permit the stem N of the device to slide loosely backward and forward. The plungers P P' located on the threaded ends of the stem N are similar to a nut, being of a larger diameter than the stem, and of a length equal to their diameter, have recesses P² P³ provided for their reception in the holes L at each end, and in all the faces, of the cylinder A as shown in Fig. 2. The recesses P² P³ are formed sufficiently deep to contain loosely the plunger P or P' and allow them to lay embedded in the holes P² P³ leaving the end or face P⁴ flush with one of the faces of the cylinder A which may be uppermost in operation. The length of the stem N is longer than the length of the hole L such additional length being nearly equal to the length of one of the plungers P or P' so that when one plunger P is embedded in the face of the cylinder A the other one P' is projected outward some distance from the opposite face as in Fig. 3. The distance plunger P or P' projects outward from the face of the cylinder may equal the height that the pins or pegs D stand from the face of the cylinder, or may even exceed it. The stem N is preferably formed of steel, brass, or iron wire of suitable diameter with a thread N' formed at each end of a suitable pitch to engage similar threads formed in the plungers P P' which have suitable holes drilled through them for that purpose. The plungers P P' are formed of brass, alloy of lead or other heavy metal, not liable to oxidation, as may be preferable and the threads N' on the stem N are cut to form a shoulder so that when the plungers P P' are secured on the threads N' formed on the stem N of the device they shall be firmly fastened and equal in gage, one with the other, for purposes of interchange, &c.

In adjusting the device the stem N with one of the plungers P secured to one end as described is inserted in the hole L forced in the cylinder A and is pushed in or inserted until the face P⁴ is flush or level with the face of the cylinder A. This leaves the other screwed end of the stem N projecting from the other and opposite side outwardly and to which the other plunger P' is then attached by its threaded hole and firmly secured. The

device may then be freely and alternately moved so as to project one or the other of the plungers P or P' from their recesses P² P³ by rotating the cylinder.

I will now proceed to describe the use and operation of my newly invented device. The cylinder A being located in the Jacquard machine by its bearings B. B. and held in position by the collars C. C. in the usual manner, the cylinder being closed with the pattern cards S having holes S' perforated therein for needles, and holes T for engagement with the pegs or pins D, the cards S being laced together in a continuous band, by the laces W, in the usual manner. Motion is imparted in a rotary direction or manner to the cylinder by the mechanism of the loom communicating, by suitable levers, motion to the Jacquard machine of which the cylinders form a part. A hook E' in engagement with the rotating device E, contact being controlled by a spring (not shown) causes the cylinder to rotate one fourth of a revolution at each pick or movement of the lathe or batten, carrying with it a card S held upon the pins or pegs D which being perforated with suitable holes indicates the pattern to be woven for that pick. Another action of the hook, by reason of another movement of the batten, brings forward another card into engagement with the pins or pegs D of another face of the cylinder, which has then moved one fourth revolution, bringing the first mentioned card away from the needles and suspending by the pins D and laces W at the side of the cylinder A. In these two motions the releasing devices in contact with the cards remain embedded in the cylinder on their upper portion, the lower being projected outward. A third card being brought upon another face of the cylinder by the revolution of the cylinder another one fourth turn the first card during this motion leaves the pins or pegs D and falls away from the cylinder being driven from engagement by a blow or pressure imparted by the face P⁴ of the plungers P P located at each end of the cylinder, the blow or pressure being imparted by the change of the center of gravity from horizontal to vertical as in Fig. 2. The blow or pressure, given alternately from each end of the releasing device, is imparted and accelerated by the sudden motion given and imparted to the cylinder in its alternate rest and motion, as the cards are changed. Continuous action of the loom in the operation of weaving brings forward by means of the mechanism of the Jacquard machine, other cards in like manner until the whole series of pattern is used, when the first card comes into operation again. During this succession of movement the releasing devices at the proper time and position, deliver a blow or impart a pressure to each card sufficient to force that card from engagement with the pins D and permit it to follow the one preceding it and to which it is laced as in Fig. 3; without the tendency to

overlay or overlap as in Fig. 4. The devices during the rotation of the cylinder A reciprocate in the holes L, P², P³, formed to receive them in the cylinder A, each end of the device giving the blows or pressure alternately. The cylinder having four sides it is obvious that the device being provided with a plunger at each end of the stem N two only are required at each end of the cylinder as one end of the device operates on one face and the other end on another and opposite face. The holes L L are drilled transversely through the ends of the cylinder at such a distance apart longitudinally that they shall not come in contact where they cross each other centrally. By means of this device cards that by reason of roughness in the holes, adhesion, or foreign substances on the card or other reasons may have a tendency to remain in contact with the cylinder with a liability to overlap the card following when released, are released

from engagement with a degree of certainty not obtained hitherto.

Having described the operation and construction of my newly-invented releasing device for pattern-cards used in the operation of weaving and for other purposes, what I claim as new, and desire to secure by Letters Patent, is as follows:

The combination in a Jacquard mechanism, 30 of the pattern cards, and the cylinder having holes transversely through the ends thereof and pegs for positioning the cards, with plungers moving loosely in the said holes and operating by gravitation to strike the card upon 35 the rotation of the cylinder to disengage the card from the said pegs, substantially as set forth.

SQUIRE BENTLEY.
